FUSED ELECTRICAL PLUG

Application filed April 10, 1931. Serial No. 529,115.

This invention relates to electrical equipment, and has for an object the provision of an improved type of electrical plug for use in releasably connecting a flexible conductor 5 to the terminals of an electrical socket which also may be carried by a flexible conductor, or which may be disposed within a rigid structure such as a floor, or wall.

A more detailed object is the provision of 10 an electrical plug of the general character described, which is capable of making or breaking a plurality of electrical circuits simultaneously.

A further object is the provision of an electrical plug which is adapted to maintain a 15 predetermined polarity of the opposite conductors of a circuit, i. e., a plug in which means are provided for preventing the insertion of the plug within its socket, in any 20 manner other than that which will result in a predetermined polarity of the conductors to which the plug is secured.

A further object is the provision of an electrical plug as described, in which fuses 25 are interposed between the conductors and the contacts of the plug, these fuses being carried within the body of the plug itself.

A still further object is the provision of a 30 plug, wherein means are provided for attaching the conductors to the plug, in such a manner that a considerable force may be imposed upon the plug to remove it from its socket, this force being in the nature of tension upon the conductor, and still avoid any 35 possibility of severing the connection of the conductors to the plug.

A still further object is the provision of an electrical plug as described, in which 40 means are provided for resiliently pressing the contacts of the plug against those of the socket when the plug is positioned operatively therein.

A further object is to provide means for locking the plug within its socket, preventing 45 accidental removal of the plug, and requiring the exertion of conscious effort on the part of the operator, to remove the plug.

The invention possesses other objects and 50 advantageous features, some of which, with those enumerated, will be set forth in the fol-

lowing description of the invention's particular embodiment which is illustrated in the drawing accompanying and forming a part of the specification.

Referring to the drawing:

Fig. 1 is a perspective view of a plug incorporating the principles of the present invention, and showing the cover with which the plug is provided, moved to open position so as to better disclose the nature of the invention.

Fig. 2 is a vertical transverse sectional view. The plane of section is indicated by the line 2—2 of Fig. 1, and the direction of view by the arrows.

Fig. 3 is a perspective view of the plug pushed partially into its cooperative socket, to better disclose the manner of the plug's employment. Portions of the figure are broken away to reduce its size.

Fig. 4 is a horizontal sectional view taken upon the line 4—4 of Fig. 3, with the direction of view as indicated.

The plug of the present invention has been designed with the especial object in view of 75 providing convenient means for establishing the circuits whereby the reproducing unit of a dynamic loud speaker is energized, and more especially for use in conjunction with that type of sound reproducing instrument 80 which is employed to reproduce sounds accompanying action depicted cinematographically. However, it should be understood that the plug is adaptable to practically universal usage, and may be employed wherever 85 it is desired to provide means for quickly establishing and breaking one or more electrical circuits.

It should be pointed out by way of explanation of the use to which the plug of the present invention is put, that loudspeakers of the general class indicated hereinabove require two circuits, to-wit: the field circuit or the circuit associated with the field coil of the reproducing unit, and the talking circuit or the circuit whereby the moving coil of the speaker is energized. In stage installation, it has been customary to interpose fuses within the field circuit, inasmuch as this circuit ordinarily carries a considerably greater quantity 100

of current than the talking circuit. However, in all installations of which I am at present aware, it has been customary to provide these fuses in a separate wall box, or other convenient location; and inasmuch as the socket within which the plug is to be positioned in order to energize the loud speaker of a "talking" moving picture installation, is ordinarily placed in the floor of the stage, closely behind the projection screen, the fuse-box and the socket are ordinarily some distance apart, resulting in considerable inconvenience whenever the necessity arises for replacing a fuse.

Another feature in connection with the field and talking circuits of a dynamic loud speaker, is that the polarity of both these circuits must be maintained, i. e., the current must pass through both the field coil and the moving coil, in a certain predetermined direction, in order for the reproducing unit to operate satisfactorily. Accordingly, one of the features of the plug of the present invention is that its reversal in respect to the socket cooperative therewith, is positively prevented.

Specifically describing the invention in its preferred embodiment, the plug comprises a body, indicated in its entirety at 6, and composed of any suitable dielectric material such as fiber or its equivalent. A projection 7, preferably of reduced width, extends from the lower end of the body 6, and is provided with preferably a pair of spaced slots 8, both slots being in the same side of the projection 7. As is clearly indicated upon Fig. 2, the bottom 9 of each of the slots 8, instead of being parallel to the sides of the plug, inclines from the bottom 11 of the plug, upward and toward that side thereof in which the slots 8 are disposed. A contact 12 of suitable conductive material, is secured to the bottom 9 of each of the slots 8, in any suitable manner, such as by countersunk screws 13 threaded into the material of which the body 6 is composed.

A recess 14 is formed in the body 6, in registry with the upper end of each of the slots 8, preferably the bottom of each recess 14 being offset from the bottom 9 of the associated slot 8, as clearly shown upon Fig. 2. The upper end of each of the contacts 12 is sigmoidal in configuration, so as to dispose the extreme upper end 16 against the bottom of the associated recess 14. Wings 18 are formed upon the extreme upper end 16 of each contact, these wings 18 being curved laterally in respect to the entire plug assembly, to resiliently grasp one of the contact ends 19 of a conventional cartridge fuse 21; with the result that the extreme upper end 16 of each contact 12 provides a spring clip for resiliently retaining and establishing electrical connection with one terminal of the fuse 21. A similar spring clip 22 is provided in the opposite end of each of the recesses 14, to accommodate the other terminal 23 of the associated fuse 21. Conductors 24 are releasably

connected to the spring clips 22, by means of terminal screws 26 threaded into the clips 22, and extend through the top of the body 6, recesses 27 extending from the upper ends of the recesses 14 to the top of the plug being provided for the accommodation of these conductors 24.

A second pair of contacts 31 are provided upon the side edges of the extension 7 of the body 6, each contact 31 being rigidly attached thereto as by screws 32 or their equivalent. Each contact 31 is provided with a tongue 33 severed therefrom along all but one of its edges, and deflected outwards slightly, as clearly shown upon Fig. 1. Each contact 31 is also provided with a terminal screw 34 threaded into the associated contact 31, or into the material of the plug itself, or both. By means of these terminal screws 34, conductors 36 may be releasably attached to the contacts 31, these conductors 36 extending from the shoulders 37 defining the upper end of the projection 7, to the top of the plug, through recesses 38 spaced from the recesses 27. Preferably, all four of the conductors 24 and 36 are gathered into a single braided conductor 39, in which the several conductors 24 and 36 are insulated from each other. A clamp 41 is rigidly attached to the conductor 39, closely adjacent that point at which the several conductors 24 and 36 diverge, the clamp 41 being firmly secured to the conductor 39, through the expedient of its being split at one side thereof, and having screws 42 extending through opposed flanges 43; with the result that by tightening the screws 42, the flanges 43 may be pressed together to secure the clamp 41 firmly to the conductor 39. The bottom of the clamp 41 is extended laterally, so that flanges 44 rigid therewith may embrace three sides of the top of the plug, screws 46 extending through the flanges 44, so as to rigidly and removably attach the clamp 41 to the top of the plug. A collar 47, which is connected to the plate 48 of the clamp 41 by a chain 49, is clamped upon the multiple conductor 39 in such position that any tension imposed upon the conductor 39 will be taken by the chain 49, rather than by that portion of the conductor 39 at the point where it extends out of the clamp 41. This arrangement permits removal of the assembled plug from its associated socket, by exerting tension upon the conductor 39, and avoids the liability of severing the connection of one or more of the conductors 24 or 36, with its associated terminal screw 26 or 34, respectively, and also protects the conductor 39 by preventing the portion thereof which receives the greatest amount of flexure, from being subjected to tension.

A closure 51 is hingedly attached to the body portion 6 by a hinge 52, permitting the closure 51 optionally to be swung to open position, as shown upon Fig. 1, or to closed position,

tion, as shown upon Fig. 3, wherein the closure overlies the recesses 14, 27 and 38, to effectually conceal the conductors 24 and 36, and the fuses 21 with their spring clips 22 and 18. The closure 51 is releasably held in closed position, through the expedient of hinge knuckles 53 and 54 carried by the body 6 and closure 51, respectively, and which move into alinement when the closure is moved to closed position to receive a removable pin 56. The closure 51 is also provided with suitable recesses 57 and 58 adapted to register with the recesses 27 and 38, respectively, when the closure is closed, to better accommodate the conductors 24 and 36, respectively.

The plug hereinabove described, is designed primarily for operation in connection with the conventional socket or "pocket" as it is termed in the trade, ordinarily employed for theatrical use. Such a socket is indicated in its entirety by the character 61, and is shown as being set flush with the floor 62 of a stage, or with the outer surface of a wall. It is conventionally provided with spaced spring contacts 63 with which conductors 64 are in communication, these contacts 63 being spaced along one side of the socket 61, in registration with the recesses 8 of the plug 6. The socket 61 is also provided with contacts 66 at the ends of the socket, and with which conductors 67 are in communication. When the plug 6 is thrust into the socket 61, the upper ends of the contacts 63 come into engagement with the contacts 12, which, on account of their obliquity, deform the contacts 63 as movement of the plug 6 into the socket 61 continues. As a result, the contacts 63 are resiliently pressed against the contacts 12, to insure good electrical contact, which is also enhanced by the wiping engagement of the contacts 12 with the contacts 63, as inward movement of the plug 6 takes place.

Simultaneously with the engagement of the contacts 12 and 63, the contacts 31 engage the contacts 66. Efficiency of this electrical connection is insured by the spring tongues 33 which resiliently press outward against the contacts 66 when the plug is in operative position, as will be readily understood.

Means are provided for retaining the plug 6 within its socket 61 against accidental removal. A detent in the form of a plate 71 is slidably mounted adjacent the lower end of the plug, and is urged by a spring 72 to extend its end into a keeper 73 provided adjacent the bottom of the socket 61. Hence, the plug cannot be removed unless the plate 71 is withdrawn against the action of the spring 72. For this purpose a rod 74 is provided, extending from the top of the plug 6 to the plate 71, within which a hole 76 is formed to receive a wedge 77 carried by the rod 74. A spring 78 under compression between the top of the plug 6 and a head 79 on the rod

74, normally holds the wedge 77 retracted from the hole 76, so that the spring 72 can push the plate 71 into the keeper 73, but by depressing the head 79, the wedge may be pushed into the hole 76, engaging the plate 71, so as to pull it away from the keeper 73, whereupon the plug 6 may be pulled out of its socket.

As stated hereinabove, the plug of the present invention is designed primarily for use in connection with the circuits whereby dynamic loud speakers are energized, particularly those sound reproducing devices used in connection with reproduction of sound accompanying cinematographic depiction of action. Such sound reproducers require two independent circuits termed the "field coil circuit" and the "talking circuit." The conductors 24 of my plug are intended to carry the field coil circuit, inasmuch as this circuit requires a heavier current than the talking circuit. The amount of current flowing through the talking circuit is so slight that no need is presented for providing fuses therein; consequently, the unfused conductors 36 are intended to convey the current of the talking circuit. The socket 61 is ordinarily employed for each of the sound reproducing devices of a bank or tower of the conventional installation. Ordinarily, there are four loud speakers distributed about the back of the moving picture screen, and consequently there will be four sockets 61 in the floor 62 of the stage, at a convenient location to permit insertion of a plug 6 within each socket 61, it being understood that the conductor 39 of each plug 6 leads to one of the electrical reproducing units of the bank of speakers. Obviously, the inclusion of the fuse 21 within the plug, dispenses with the necessity of employing a separate fuse-box.

It is to be understood that the details of the invention as herein disclosed, are subject to alteration within the spirit or scope of the appended claims.

I claim:

1. An electrical plug comprising a body of insulative material, a plurality of electrical contacts lying entirely within individual recesses in a common lateral side of the body, and a conductor connected to each contact.

2. An electrical plug cooperative with a socket having a plurality of differentiated pairs of electrical contacts therein, said plug comprising a body of insulative material receivable within said socket, a plurality of pairs of electrical contacts carried by said plug and differentiated similarly to those of the socket, and means for bringing contacts of the plug into engagement with the associated contacts of the socket when the plug is inserted therein.

3. An electrical plug comprising a body of insulative material, a plurality of electrical contacts set within recesses in a com-

mon side of the body, and a conductor connected to each of said contacts, said contacts being inclined from the bottom of said plug toward the said side thereof.

5. 4. An electrical plug cooperative with a socket having a plurality of structurally differentiated pairs of electrical contacts therein, said plug comprising a body of insulative material receivable within said socket, a plurality of pairs of electrical contacts carried by said plug and differentiated similarly to those of the socket, means for bringing contacts of the plug into engagement with the associated contacts of the socket when the plug is inserted therein, an electrical conductor connected to each of said plug contacts, means associated with each of said plug contacts for resiliently pressing them against the associated socket contacts, and fuses interposed between certain of said conductors and their associated contacts.

5. In combination, an electrical plug connector, a socket member therefor, and releasable means for locking said plug within said socket member, said locking means comprising a detent carried by said plug, means pressing said detent into extended position wherein said detent engages said socket member, and means operative to withdraw said detent.

6. An electrical connector comprising a plug member, a socket member adapted to receive said socket member, contacts carried by said members and adapted to electrically engage each other when said plug member is disposed within said socket member, a movable detent carried by one of said members and adapted to engage the other member to retain the plug member within the socket member, and means for withdrawing said detent.

In testimony whereof I have signed my name to this specification.

LEONARD L. MAXAM.
